UNITED STATES PATENT OFFICE.

RUDOLPH BOARDMAN BOYLE, OF KANSAS CITY, MISSOURI.

AUTOMATIC TRAIN-STOPPING DEVICE.

1,424,980.

Specification of Letters Patent. Patented Aug. 8, 1922.

Application filed October 9, 1920. Serial No. 415,799.

To all whom it may concern:

Be it known that I, RUDOLPH B. BOYLE, a citizen of the United States, and a resident of Kansas City, in the county of Jackson and 5 State of Missouri, have invented a new and useful Improvement in Automatic Train-Stopping Devices, of which the following is a full, clear, and exact description.

My invention relates to improvements in 10 automatic train stopping devices, and it consists in the combinations, constructions and arrangements herein described and claimed.

An object of my invention is to provide a 15 device, by means of which the stopping of trains may be accomplished automatically, either from a train dispatcher's office, or by a flagman.

A further object of my invention is to provide a train stopping device, in which the 20 air in the main brake line is released by the positive opening of the main brake line, when cooperating apparatus has been set by either the train dispatcher or the flagman.

A further object of my invention is to provide 25 an explosive unit of novel form, which, when operated, will cause the opening of the main brake line, and which may be readily replaced when it is desired to proceed.

Other objects and advantages will appear 30 in the following specification, and the novel features of the invention will be particularly pointed out in the appended claims.

My invention is illustrated in the accompanying drawings, forming part of this application, in which—

Figure 1 is a diagrammatical view, showing a track equipment,

Figure 2 is a diagrammatical view, showing the circuit connections at a dispatcher's 40 office, and at a flagman's station, and their connection with the train stopping mechanism,

Figure 3 is a perspective view, showing a portion of a track equipped with a contact 45 rail or ramp,

Figure 4 is a sectional detail view of a portion of the main brake line, and one of the explosive units inserted therein, and

Figure 5 is a section along the line 5—5 50 of Figure 4.

Referring now particularly to Figure 1, I have shown therein a track, comprising the rails 1 and 2. At certain intervals between the track rails are disposed contact rails 3, like that shown in

Figure 3. These contact rails, as will be observed, are beveled at their ends, as at 3_a in the drawings, and are preferably mounted on insulating supports 4. In Figure 1, I have shown two dispatcher's offices at A and B respectively. On the poles 5 at stated intervals are boxes 6, which are designed to be used by the flagmen. In Figure 1, there is a box 6 on each pole, but in actual practice, the boxes would not be located so closely together. Each box has two contacts 7 and 8, which are connected with the line wires 9 and 10 respectively. The numeral 11 indicates a neutral point, upon which the switch arm 12 in the box 6 may rest. Normally, this 60 arm is in the position shown in Figure 6. It is connected, by means of a conductor 13, with the nearest ramp. or contact rail 3, as shown in Figure 2.

At each dispatcher's office is a battery X, 75 which is preferably grounded on one side, and is connected with a switch arm 14 in a switch box 15, having contacts 16, 17 and 18 respectively. Normally, the switch arm 14 is on the contact 17, which is connected by a 80 conductor 19 with the wire 10. The wire 9 is connected to the contact 16, while the contact 18 is connected to a wire 20, leading in the opposite direction, so that the train dispatcher can control sections of track, either 85 to the right or to the left, in Figures 1 and 2. In Figure 2, I have shown diagrammatically a spring contact 21, which is fastened to some part of each locomotive, such, for instance, as the cowcatcher, shown diagrammatically at 22. This spring is connected, by means of the conductor 23, with the primary circuit of an induction coil 24, the other terminal of the primary circuit of the induction coil being preferably grounded by 90 a conductor 25 on a convenient portion of the locomotive frame.

Referring now to Figure 4, I have shown therein the main brake line 26, in which is disposed a T, 27. The explosive device comprises a brittle glass casing 28 which is adapted to enter one end of the T, and which is provided with a metal ring 29, having threads arranged to enter the threaded portion of the T. In Figure 5, this ring 29 is 100 shown as being split, in order that it may be placed in position. A packing material 30 is preferably placed in the circular groove formed in the frame body portion, and then the ring, which is of spring metal, such as 105 110

copper or brass, is sprung into position, so that when the latter is screwed into the T, an air tight joint is made.

The glass body portion is threaded at 31 to receive a threaded spider 32. The latter bears a cartridge 33, containing an explosive 34, such as fulminate of mercury. This cartridge is covered with a thimble 35 of cast iron, which is serrated at 36, so as to break into pieces when the cartridge or container is exploded. At 37 I have shown spark terminals, which are connected by means of wires 38 and 39 with the secondary circuit of the induction coil.

15 From the foregoing description of the various parts of the device, the operation thereof may be readily understood. Normally, the apparatus is as shown in Figure 2. Let us assume that a train has a hot box,

20 and is forced to stop. The flagman is sent back to stop the train in the rear. As he comes to the first box 6, he throws the switch arm 12 from the position shown in Figure 2 over to the contact 8. This connects the contact rail 3 with the battery X at the dispatcher's office. The flagman then proceeds to the second box, and does the same thing over.

Taking his position at the side of the track, he attempts to flag the oncoming train. For some reason, the oncoming train does not catch his signal. As the spring 21 of the oncoming train comes in contact with the first charge rail 3, current is sent through the coil 24, and the current from the latter explodes, the charge 34 shattering the glass casing 28 and permitting the air in the main brake line to escape, that is, setting the brakes and stopping the train.

Let us assume another situation. A train 40 leaves a station on schedule time. Immediately after leaving the station, a wire comes in to the conductor to hold the train, for a special has been given the right of way. Obviously, there is great danger of collision under these circumstances. The train dispatcher needs only to shift his switch arm 14 to the contact 16, when he will place all contact rails 3 on the section to the left of the dispatcher's attention, in Figure 2, in direct

50 connection with the battery. Either of the

trains will be stopped automatically, when their spring contacts 21 come into engagement with the first charged rail 3. Collision will thus be avoided, and the conductors of the trains will be warned of impending danger, and will, of course, await further instructions before proceeding. These instructions can be procured by use of telephone boxes or cut-in stations for telegraph instruments, or other devices, which form no part of the present invention.

Each locomotive may have on board a supply of the explosive units, such as that shown in Figure 4, so that when the train is stopped, it is only the work of a few minutes to remove the fractured unit and insert a new one in lieu thereof before again turning on the air pressure on the main brake line.

While I have mentioned fulminate of mercury as being an explosive which may be used, it is obvious that any suitable explosive, which may be fired by an electric current, might be used in lieu thereof, without departing from the spirit of the invention.

I claim:

1. In a train stopping device, a track, a plurality of ramps disposed along the track, a pair of line wires, a switch box for each ramp, means in said switch box for connecting each ramp with either of said line wires, a dispatcher station, a switch box at said dispatcher station, a source of current, and means in the switch box at the dispatcher station for connecting said source of current with either of said line wires.

2. In a train stopping device, the combination of a track, a plurality of ramps disposed between the rails of the track, a switch box for each ramp, a switch arm disposed in each box, each of said arms being connected with one of said ramps, a pair of line wires, terminals in said box for connecting said switch arm with either of said line wires, a dispatcher station, having a switch box, a battery, and a switch arm in the switch box at the dispatcher station for connecting the battery of either of said line wires.

RUDOLPH BOARDMAN BOYLE.
